US00D588450S

(12) **United States Design Patent**
Snedden et al.

(10) **Patent No.:** **US D588,450 S**
(45) **Date of Patent:** **** Mar. 17, 2009**

(54) **FOOD CONTAINER**

(75) Inventors: **Craig Richard Snedden**, Culver City, CA (US); **Gandhi Bonergue Sifuentes**, Whittier, CA (US)

(73) Assignee: **Direct Pack, Inc.**, Sun Valley, CA (US)

(**) Term: **14 Years**

(21) Appl. No.: **29/306,356**

(22) Filed: **Apr. 8, 2008**

(51) LOC (9) Cl. **09-03**

(52) U.S. Cl. **D9/424**

(58) Field of Classification Search **D9/424, D9/414, 418, 420-423, 425, 430, 432; D3/273; D7/550.1, 601, 602, 629, 206/216, 457, 206/508, 541, 557, 815, 822; 220/213, 376, 220/601, 669, 674, 675, 783, 789, 790, 796, 220/797; 229/116.1, 229.406, 407, 902, 229/903, 904, 905, 906, 938; 426/106**

CLAIM

The ornamental design for a food container, as shown and described.

DESCRIPTION

FIG. 1 is a top perspective view of a food container showing our new design;

FIG. 2 is a top plan view thereof;

FIG. 3 is a front elevational view thereof;

FIG. 4 is a bottom plan view thereof;

FIG. 5 is a right elevational view thereof;

FIG. 6 is a left elevational view thereof; and,

FIG. 7 is a back elevational view thereof.

The lid shown in broken lines is unclaimed environment, and forms no part of the claimed design.
